MANUFACTURE OF MINIATURE INCANDESCENT LAMPS

Reginald K. Braunsdorff, East Orange, N. J., assignor to Tung-Sol Lamp Works, Inc., Newark, N. J., a corporation of Delaware

Application May 31, 1941, Serial No. 396,013

3 Claims. (Cl. 176—36)

This invention relates to the manufacture of miniature lamps and particularly miniature lamps of the very small variety such, for example, as lamps for recording phonographs, panel boards, flash lights, and the like.

Miniature lamps of this character embody a pair of slender support and lead wires which are fused to and held in spaced relation from each other by a refractory or glass bead, with the filament mounted on the free ends of the lead wires and with the ends of these slender lead wires which are disposed on the opposite side of the bead from the filament being sealed between the top tube and the bulb when the two are sealed together and forming the sole support for the stem. It has been found that in lamps of this character vibrations are transmitted to the mount through the long slender lead and support wires which form a two-point support. These vibrations not only shorten the life of the lamp but also render the lamp extremely inefficient for certain uses. For example, when vibrations of the mount occur in miniature lamps used for recording phonographs, distortion occurs in the reproduction with consequent loss of time and expense, and such vibrations occur irrespective of the age of the lamp. The standard miniature lamp has a resonance point of vibration between 200 and 4000 cycles per second, depending upon the exact lamp construction. This resonant vibration when the lamp is used in recording phonographs is established by some critical note or vibration as played back or set up by a phonograph record. Vibrations also occur at harmonics of the resonance frequency. Such vibrations of the mount of the lamp, once set up, tend to prolong themselves even after the note which initiated the vibration has been completed. The expedient of increasing the size of the support wires or of merely providing one or more additional support wires proved unsatisfactory.

One object of the invention is a novel and improved method of manufacture of a miniature lamp with multiple mount support wires whereby the objectionable vibrations above described are substantially eliminated and the operation of the lamp is improved.

Further objects of the invention will herein-after appear.

For a better understanding of the invention reference may be had to the accompanying drawing forming a part of this application, wherein

Figs. 1 to 4 illustrate steps in the manufacture of a lamp bulb in accordance with the invention; and

Fig. 5 is a view at right angles to Fig. 4 showing the completed lamp.

Referring to Figs. 4 and 5 of the drawing, a miniature lamp embodying the invention is illustrated. This lamp embodies a bulb 1, the

conventional small filament 2 and the conventional slender leads 3, the latter being, for example, of approximately .01 diameter, the drawing illustrating these leads on an exaggerated scale. The leads 3 are spaced from each other and held in spaced relation by a conventional mount bead 4 as, for example, of glass or other refractory fusible material, and in the conventional lamp bulb the lower parts 3' of the leads 3 form the sole support for the bead 4 and the filament 2'; these leads 3' being sealed between the top tube 5 and the neck 1' of the bulb according to the conventional manufacture of standard tipless mounts. The bulb of my invention embodies, in addition to these conventional parts, a supporting wire 6 which is anchored to the bead 4 at one end and is bent downwardly with its end 6' sealed into the top tube and the neck of the bulb when the top tube and the bulb neck are fused together. The stem is thereby supported and held against vibration by the leads 3, 3' and by the anchor or guide wire 6, thus resulting in a tripod support by the fusion of the leads and the support wire 6 at the points 7, 8 and 9 into the seal formed between the top tube 5 and the neck 1' of the bulb. The leg 6 of the tripod support may be of the same metal as the leads 3, as for example the conventional Dumet leads, and may be of the same small diameter as the leads 3, or it may be even smaller in diameter.

Figs. 1, 2 and 3 illustrate steps in the manufacture of the bulb. The leg 6 has one end thereof inserted lengthwise into the peripheral edge of the bead 4 at a point out of line with the lead wires 3 as shown in Fig. 1. This leg is then bent downwardly to a position such that its lower end 6' is in a position to be pressed into the fused glass formed at the seal between the bulb neck 1' and the top tube 5. This position is indicated roughly in Fig. 3. With the parts assembled as shown in Fig. 3, the end of the neck 1' and the adjacent end of the top tube 5 are fused and pressed together in sealing relation, the end 45 6' of the leg 6 being simultaneously embedded in the fused mass at this juncture, as for example illustrated in Figs. 4 and 5. After the top tube is sealed off at 5', a conventional base 10 is attached. In the particular embodiment of the invention exhibited, the bead 4 is slightly wider in the plane of the wire 3, 3' than it is in the plane transverse to the plane of the wires and the anchor wire 6 is inserted into the edge 50 of the bead at a point which is substantially equi-distant from the points where the support wires 3, 3' pass through the bead or which is roughly 90° removed therefrom on an arc joining all three points.

This construction of miniature incandescent lamp eliminates and prevents any period of vibra-

tion, and particularly harmful vibrations which are transmitted to the bead 4 and filament 2, with the result that lamps of this character not only tend to endure for their normal life with a minimum of premature failures, but also are eminently satisfactory for use in apparatus such as recording phonographs in which vibration would have deleterious effect upon the operation of the apparatus.

I claim:

1. The method of manufacturing a miniature incandescent lamp having a top tube fastened to the bulb neck thereof which comprises the steps of fusing a pair of leads to a refractory bead support and spacer, sealing an anchor support wire endwise to said bead at a point out of line with the points where the leads are fused, fusing a top tube endwise to the neck of the bulb, and during the last named fusing operation embedding said lead wires and said anchor wire into the mass of fused glass formed at the juncture between the neck and the top tube.

2. The method of manufacturing a miniature incandescent lamp comprising the steps of fusing and fastening a pair of leads to a support-

ing and spacing refractory bead, sealing an anchor wire endwise to said bead at a point ninety degrees removed from the points where the lead wires pass through the bead, forming the ends 5 of the lead wires and the anchor wire into diverging relation so as to extend into the vicinity of the end of the bulb neck, fusing a top tube endwise to the bulb neck and simultaneously embedding the lead wires and the anchor wire 10 into the mass of fused glass formed at the juncture between the neck and the top tube.

3. The method of manufacturing a miniature incandescent lamp having a top tube fastened to the bulb neck thereof which comprises the steps 15 of fusing a pair of leads to a refractory bead support and spacer, sealing an anchor support wire endwise to said bead at a point out of line with the points where the leads are fused and on the peripheral edge of the bead, fusing a top tube endwise to the neck of the bulb, and during the last named fusing operation embedding said lead wires and said anchor wire into the mass of fused glass formed at the juncture between the neck and the top tube.

25 REGINALD K. BRAUNSDORFF.
